CONVERSION OF HYDROCARBONS

Delos E. Bown, Henry G. Schutze, and Albert T. Watson, Baytown, Tex., assignors, by mesne assignments, to Esso Research and Engineering Company, Elizabeth, N.J., a corporation of Delaware

Original application May 27, 1957, Ser. No. 661,830. Divided and this application Mar. 7, 1963, Ser. No. 265,304

3 Claims. (Cl. 260—683.2)

This application is a division of Serial No. 661,830, now abandoned, entitled "Conversion of Hydrocarbons" filed May 27, 1957, for Messrs. Delos E. Bown, Henry G. Schutze and Albert T. Watson.

The present invention is directed to a method for converting hydrocarbons. More particularly, the invention is concerned with the conversion of hydrocarbons in the vapor phase employing a catalyst. In its more specific aspects, the invention is concerned with the catalytic conversion of hydrocarbons employing a catalyst which converts the hydrocarbons to selective hydrocarbons.

The invention may be briefly described as a method for converting hydrocarbons in which a hydrocarbon feed in the vapor phase is contacted with a catalyst consisting of a partially reduced amphoteric metal compound, which is substantially free from extraneous chain propagating agents, under conditions to form a converted product.

The present invention may also be described as a method for producing valuable hydrocarbons which consists of reducing an amphoteric metal compound to form an amphoteric metal compound of a lower valency. The amphoteric metal compound of lower valency is then recovered in a substantially purified form. A hydrocarbon feed stock in a vaporized condition is then contacted with the recovered amphoteric metal compound to form a converted hydrocarbon from the vaporized hydrocarbon.

The hydrocarbons forming the feed stock of the present invention may be in a purified condition but may be a mixture of the several hydrocarbons. For example, the hydrocarbons may be olefins or paraffins having from about 2 to about 6 carbon atoms. As examples of these hydrocarbons may be mentioned, by way of illustration and not by way of limitation, ethylene, propylene, isobutane, normal butane, the butylenes, including the cis- and trans-isomers, the pentylenes, pentanes, hexanes, hexylenes, and the higher members of the several homologous series.

It is further contemplated that the feed stocks of the present invention will employ hydrocarbons from the gasoline boiling range up through the gas oil boiling range. For example, hydrocarbons boiling from about 60° up to about 800° F. may suitably be employed. The hydrocarbons in this boiling range may be in purified condition or may be in mixture with other hydrocarbons. It is contemplated that the hydrocarbons may suitably be mixtures of olefins, paraffins and naphthenes.

The reactions which may be employed in the conversion method of the present invention include, by way of illustration and not by way of limitation, isomerization of olefins by shifting the double bond; for example, from a 1 to a 2 position; isomerization by skeletal rearrangement of olefins and paraffins; alkylation of isoparaffins and olefins; dimerization and trimerization of olefins; cracking of gasoline and heavier hydrocarbons; and cyclization of olefins having a long chain to form ring compounds, such as cyclohexene, benzene, and the like.

The temperatures employed in the practice of the present invention may range from about 60° F. up to about 1000° F. Preferred temperatures may range from about 200°

2

to 800° F., with temperatures in the latter range being from about 200° to about 600° F.

Pressures suitable in the practice of the present invention range from atmospheric pressure to about 800 pounds per square inch gauge. A preferred range of pressures is from about 100 pounds per square inch gauge up to about 500 pounds per square inch gauge.

Space velocities may range from about 0.25 up to about 500 v./v./hr. It is to be noted that these space velocities are gas space velocities, since the reaction is conducted in the gaseous or vapor phase.

The catalysts employed in the practice of the present invention are partially reduced compounds of the amphoteric metals having at least two oxidation states and preferably compounds of groups IV, V and VI of the periodic arrangement of the elements (Ref. Periodic Chart of the Elements, 1947 Edition, H. D. Hubbard, W. M. Welch Manufacturing Company, Chicago, Ill.). Representative catalysts useful in the practice of the present invention are the partially reduced halides, oxyhalides, oxides, hydroxides and organic compounds, such as alcohols, acetates, benzoates and acetyl acetones of the transition metals of Groups IV, V, and VI of the Periodic System; for example, the compounds of the metals such as titanium, zirconium, hafnium, thorium, uranium, vanadium, niobium, tantalum, chromium, molybdenum, tungsten, iron, cobalt and nickel. The metal halides, particularly the chlorides, are generally preferred in the practice of the present invention. For example, titanium trichloride and zirconium trichloride are preferred as being the most active of these metals. While the trichlorides are preferred, the corresponding bromides may be used.

The present invention is based on the discovery that the amphoteric metal compounds may be reduced to form an active catalyst which is recovered for employment to convert the hydrocarbons of the type mentioned before. A feature of the present invention is employing a partially reduced amphoteric metal compound which is substantially free from chain propagating agents. In a word, it is contemplated in the present invention that the amphoteric metal compounds may be reduced under conditions such that extraneous chain propagating agents are absent or if compounds are used for reducing the amphoteric metal compound, the reduced amphoteric metal compound is substantially purified or freed of chain propagating agents. By virtue of employing a catalyst which is substantially free of chain propagating agents, it is possible to convert catalytically hydrocarbons which heretofore have not been convertible to liquid products in the particular reaction. Actually, heretofore, when employing the prior art catalysts, the products have been substantially of high molecular weight.

The present invention will be further illustrated by reference to the drawing in which:

FIG. 1 is in the form of a diagrammatic flow sheet of a preferred mode of converting hydrocarbons with the catalyst of the present invention; and

FIG. 2 is in the form of a diagrammatic flow sheet of another preferred mode wherein the amphoteric metal compound is reduced, purified and then employed to convert hydrocarbons.

Referring now to the drawing, and particularly to FIG. 1, numeral 11 designates a charge line by way of which a feed hydrocarbon is introduced into the system and is pumped by pump 12 into a furnace or heater 13 provided with a heating coil 14. The temperature of the hydrocarbons passing through the coil 14 is adjusted by means of burners 15 and the heated and vaporized hydrocarbon is discharged from the furnace 13 by way of line 16 and then introduced into a reaction zone 17 con-

taining a bed of catalyst 18 of the type illustrated before.

At this point it may be mentioned that while the catalyst may be used in its partially reduced form, as such, it may suitably be supported on a suitable support or carrier such as carbon, transition metal oxides, cryolite, and the like. As examples of suitable catalyst supports may be mentioned titanium oxide, nickel oxide, and nickel metal, and the like. It is understood that there are many supports which may be used for supporting the catalyst of the present invention. When a catalyst support is used, it will be desirable to incorporate about 0.5 up to about 15 percent by weight of catalyst on the support. A preferred range may be from about 3 to about 8 percent by weight. Desirable results may be obtained with about 5 percent by weight.

On passage of the vaporized hydrocarbon at a space velocity in the range from about 0.25 to about 500 v./v./hr. through the catalyst bed 18, the hydrocarbon is converted to a valuable product which issues from the reaction zone 17 by way of line 19 which introduces the product into a fractionation zone 20 which may be a series of fractional distillation zones, which for convenience is shown as a single fractional distillation tower equipped with suitable internal vapor-liquid contacting means, such as bell cap trays, bubble plates, and the like, to insure intimate contact between vapors and liquids. The fractional distillation zone 20 is also provided with a heating means or temperature adjusting means illustrated by steam coil 21 which serves to adjust temperature and pressures. It is to be understood that fractional distillation zone 20 is also provided with all auxiliary equipment usually found in a modern fractional distillation tower which will include means for inducing reflux, condensing and cooling means, reboiling means, and the like. The desired products are separated into component parts in zone 20 and are withdrawn by way of lines 22, 23, and 24, depending on the boiling range, while heavier material may be withdrawn by line 25. Any of the several withdrawn streams may be recycled, or a portion of the several streams may be recycled for further conversion. The products obtained from the reaction as described are quite useful and may be used as blending agents in gasoline or as feed stocks for further conversions, such as polymerization, cracking, hydroforming, hydrogenation, conversion to synthetic rubber, and the like.

Referring now to FIG. 2, an amphoteric metal compound such as titanium tetrachloride is introduced into the system by way of line 30 from a source not shown into a catalyst reduction zone 31. A reducing agent such as hydrogen may be introduced into reduction zone 31 by way of line 32, controlled by valve 33. In zone 31 the amphoteric metal compound is reduced to a lower valance. For example, titanium tetrachloride is reduced to titanium trichloride and/or titanium dichloride. The reduced amphoteric metal compound is withdrawn from zone 31 by line 34, and where hydrogen is employed as a reducing agent, the titanium trichloride is discharged by way of line 35 controlled by valve 36 into a reaction zone 37, which may be similar to reaction zone 17 of FIG. 1. Vaporized feed hydrocarbon at reaction temperatures is introduced by way of line 38 to zone 37 and converted products are withdrawn by line 39 into recovery zone 40, which may be similar to fractional distillation zone 20. Products may be withdrawn from zone 40 by way of lines 41, 42, 43, 44 and 45.

If the amphoteric metal compound is reduced by employing a metal alkyl, such as aluminum triethyl, the reducing agent would be introduced by way of line 32 to reduce the titanium tetrachloride to titanium trichloride. However, in this instance, valve 36 in line 35 would be closed and valve 46 in line 34 would be opened discharging the reduced amphoteric metal compound in admixture with the aluminum alkyl into a catalyst purification zone 47 wherein the titanium trichloride would be freed sub-

stantially of the aluminum alkyl by washing with a suitable solvent such as a normal paraffin introduced into zone 47 by way of line 48 controlled by valve 49. After repeated washings to remove substantially the aluminum alkyl, which is a chain propagating agent, the purified catalyst may then be discharged by line 50 into reaction zone 37 for converting the vaporized feed hydrocarbons.

As an example of reducing the amphoteric metal compound, an amphoteric metal compound such as titanium tetrachloride may be reduced by conducting a feed stream, comprising volatilized titanium tetrachloride, into a reduction zone such as 31 to bring the volatilized titanium tetrachloride in contact with a heated surface such as an electrically heated filament whereby a portion of the volatilized titanium tetrachloride is reduced to a product consisting of titanium trichloride. The reduced titanium trichloride is substantially free of the unreduced titanium tetrachloride and is employed as a catalyst in the present invention.

As a further example of a reducing operation, vaporized titanium tetrachloride may be reduced by exposure to actinic light.

The amphoteric metal compound may also be reduced as described by contacting same with an aluminum alkyl such as aluminum triethyl followed by recovery of the amphoteric metal compound to recover substantially purified amphoteric metal compounds substantially free of chain propagating agents.

The present invention may be further illustrated by the following examples.

Runs were conducted with isobutylene employing titanium trichloride which had been formed by reducing titanium tetrachloride with aluminum alkyl in which the aluminum alkyl was removed from the titanium trichloride by exhaustive washing with a solvent. The purified titanium trichloride substantially free of extraneous chain propagating agents was then employed to contact isobutylene at a temperature of 290° F. A product was recovered and found to contain 3.4 percent by volume of trans-olefins, 0.9 percent by volume of alpha-olefins, 14.1 percent by volume of tertiary olefins and 16.6 percent by volume of tri-substituted ethylenes, for a total of 35.0 percent of olefins detectable by infrared analysis, while total olefin content including tetra-substituted olefin was 90 percent. The product contained 1.0 percent by volume of C₆ hydrocarbons, 15.8 percent by volume of C₇ hydrocarbons, 48.9 percent by volume of C₈ hydrocarbons, 9.5 percent by volume of C₉ hydrocarbons, 5.6 percent by volume of C₁₀ hydrocarbons, 6.3 percent by volume of C₁₁ hydrocarbons and 12.9 percent by volume of C₁₂ hydrocarbons. The data for isobutylene feed show that the titanium trichloride substantially free of chain propagating agents may be employed to dimerize and trimerize olefinic feed stocks. Besides acting to form dimers and trimers of isobutylene, the reaction caused the formation of substantial amounts of hydrocarbons through mechanisms which may involve cracking, disproportionation, hydrogenation, and dehydrogenation, as well as alkylation and skeletal isomerization.

Additional runs were made with cis-butene-2 as a feed stock, employing in one instance a catalyst which had been prepared by reducing titanium tetrachloride in the absence of an amphoteric metal compound, and in another instance a catalyst which had been prepared by reducing titanium tetrachloride with aluminum alkyl, followed by treating the reduced catalyst to free it of extraneous chain propagating agents by repeated washings with a solvent. These runs are shown in the following table where the run with the first catalyst is shown as Run No. 1, and the run with the second catalyst as Run No. 2. In both instances, with cis-butene-2, temperatures of 350° F. were employed.

A third run was made employing a catalyst reduced in the same manner as that of Run No. 1 using cis-butene-2

and employing a temperature of 1000° F. These three runs are shown in the following table:

Table I

	Run No. 1	Run No. 2	5
Butene-1	3.1	13.0	10
Trans-butene-2	17.9	42.1	
Cis-butene-2	79.0	38.7	
N-butane	0	0.8	
Iso-butane	0	5.4	
			Run No. 3
Butene-1		24.2	25
Trans-butene		35.3	
Cis-butene		40.5	

These runs show that at temperatures of 350° and 1000° F. the cis-butene-2 may be isomerized by shifting of the double bond.

Runs were also made with butene-1 with the catalyst employed in Run No. 1 in the immediately preceding table. In this operation in Run No. 4 the butene-1 was contacted with the substantially pure titanium trichloride at a temperature of 475° F., whereas in Run No. 5 a temperature of 750° F. was employed. The data for the runs 4 and 5 are represented in the following table:

Table II

	Run No. 4	Run No. 5	25
Butene-1	42.8	42.7	
Trans-butene-2	32.8	33.9	
Cis-butene-2	24.4	23.4	

Additional runs were made on a charge mixture consisting of 90.5 percent by volume of cis-butene-2 and 9.5 percent by volume of trans-butene-2. Operations were conducted at several temperatures employing as a catalyst titanium trichloride which was substantially free of chain propagating agents. The results presented in the following table were obtained.

Table III

Temp., ° F.	Butene-1	Trans-butene-2	Cis-butene-2
350	3	15	82
450	14	45	41
500	16	56	28

It will be seen from the data in the foregoing table that the cis-butene-2 had been substantially isomerized to trans-butene-2 and to butene-1.

Additional runs were made with the titanium trichloride catalyst substantially free of chain propagating agents with the titanium trichloride supported on titanium dioxide. Runs were conducted at varying temperatures charging the same feed stock consisting of 90.5 percent by volume of cis-butene-2 and 9.5 percent by volume of trans-butene-2. The results of these runs are shown in the following table:

Table IV

Temp., ° F.	Butene-1	Trans-butene-2	Cis-butene-2
560	5	15	80
600	7	16	77
650	9	18	73
700	12	23	65
750	17	32	51
800	21	38	41
925	24	38	38
990	25	37	38

It will be seen from the runs in the immediately preceding table that the supported titanium trichloride also gives isomerization of the cis-butene-2 to trans-butene-2 and to butene-1.

Runs were then made in converting olefinic hydrocarbons employing catalysts in accordance with the present invention where the catalysts were partially reduced by several methods. In each case the catalysts were washed with a hydrocarbon solvent, such as n-heptane, dried and placed in a bed in a reaction zone.

The results of these several runs, giving the olefin feed, the conditions, conversions and analysis of liquid products are presented in Table V:

Runs F-23, F-24, F-33 and P-11 were with a reduced amphoteric metal catalyst in which titanium tetrachloride was reduced using an aluminum alkyl. In each instance the washing operation removed chain propagating agents from the catalyst and the catalyst consisted essentially of titanium trichloride. In Runs F-10 and F-34, the titanium trichloride employed was formed by reducing titanium tetrachloride with hydrogen. Washing of the catalyst with the hexane solvent removed chain propagating agents. In Run P-13, the titanium trichloride catalyst employed was prepared similarly to Run F-34. In Run P-5, titanium tetrachloride was reduced with a nickel-aluminum alloy to form titanium trichloride supported on nickel, the aluminum being consumed in the reducing operation and aluminum chloride resulting therefrom being removed by a sublimation operation.

In Runs F-37, F-38, and F-39, titanium tetrachloride was reduced by irradiation in a Van de Graaff accelerator with the chain propagating agent, if any, removed by the washing operation.

The results of the runs presented in Table V show, comparing Runs F-10 and P-13, which employed the same catalyst, that the pressure exerts a significant effect on conversion to liquids. No liquids were obtained in F-10 whereas 27 percent conversion to liquid products was obtained in P-13.

It is noteworthy from the analysis of the products that while the products contain substantial percentages of olefins, a substantial amount of saturated hydrocarbons was also produced, reference being had particularly to Runs F-33, F-24 and P-5. It will be noted that in Run F-33, 56 percent of the liquid product was olefinic, while the remainder was saturated hydrocarbons. Likewise, with respect to Run F-24, 57.8 percent of the liquid product was olefinic with the remainder being saturated hydrocarbons. In Run P-5, a predominant portion of the product was saturated hydrocarbons.

The presence of saturated hydrocarbons may be explained by reactions which may involve hydrogenation, disproportionation, alkylation and possibly skeletal isomerization.

It may be seen from the several preceding examples that the practice of the present invention allows the isomerization of olefins by shifting of the double bond and also the dimerization and trimerization of olefins such as propylene, butene-1, butene-2 and isobutylene.

While the invention has been illustrated specifically by isomerization, dimerization and trimerization reactions, it is not to be limited to such reactions. For example, isoparaffins and olefins may be alkylated by employing temperatures within the range given and employing a feed stock which contains a mixture of isoparaffins and olefins; for example, isobutane and butylenes. In such opera-

tions, the isoparaffins should be used in excess, as exemplary, a feed stock containing about 3 mols of isobutane per mol of butylene may be satisfactory. The alkylation technique is well known in the art and further details thereof are not required. Likewise, for skeletal isomerization of either olefins or paraffins, it may be desirable to operate in the upper portion of the temperature range employing olefinic hydrocarbon feeds having higher boiling ranges than those employed in the several examples given supra.

In the cracking of hydrocarbons employing the catalyst of the present invention, it may be desirable to use temperatures in the upper portion of the range and to use gasoline, kerosene and gas oil hydrocarbons as the feed stock. As exemplary only, it may be desirable to charge a feed stock in the gas oil boiling range to a reaction zone containing a catalyst of a partially reduced amphoteric metal compound free of chain propagating agents at a temperature ranging from about 500° up to about 1000° F.

In cyclization reactions, it will be desirable to select an olefin which has a sufficiently long chain to form a cyclic compound of the type illustrated. For example, it may be desirable to employ an olefin having at least 6 carbon atoms for a cyclization reaction. As an example of an olefinic feed stock, reference may be made to 1,5 hexadiene. Other olefinic hydrocarbons of suitable chain length may also be used.

The nature and objects of the present invention having been completely described and illustrated, what we wish to claim as new and useful and secure by Letters Patent is:

1. A method for isomerization of olefins which consists of contacting a butylene in the vapor phase with reduced titanium tetrachloride catalyst consisting of purified titanium trichloride at a temperature in the range of 350° to 1000° F. at a space velocity in the range from about 0.25 to about 500 v./v./hr. to form a product containing an isomer of said butylene, and recovering said product.

2. A method in accordance with claim 1 in which the butylene is cis-butene-2.

3. A method in accordance with claim 1 in which the butylene is butene-1.
